UNITED STATES PATENT OFFICE.

HARVEY S. BONNELL, OF GUTHRIE, OKLAHOMA TERRITORY.

THRASHING-MACHINE.

SPECIFICATION forming part of Letters Patent No. 553,894, dated February 4, 1896.

Application filed March 20, 1895. Serial No. 542,517. (No model.)

To all whom it may concern:

Be it known that I, HARVEY S. BONNELL, a citizen of the United States, residing at Guthrie, in the county of Logan and Territory of 5 Oklahoma, have invented a new and useful Thrashing-Machine, of which the following is a specification.

This invention relates to certain new and useful improvements in the construction of 10 thrashing-machines, and has for its object to provide a more rapid and efficient separation of the grain from the chaff and straw and a thorough and more effective cleaning of the same, with less liability of waste from blowing 15 the grain over, than is possible with similar machines as heretofore constructed.

The improvement consists in combining with a thrashing-machine of ordinary construction a fan to co-operate with the fan usually 20 provided and to dispose the same with reference to the separating-screens and the shoe, and to improve the general construction of the machine whereby the parts are compactly arranged so as to attain the desired results in a thorough and satisfactory manner. 25

The improvement also consists of the novel features and peculiar construction and combination of the parts, which hereinafter will be more fully described and claimed, and which 30 are shown in the accompanying drawings, in which—

Figure 1 is a side elevation of a thrashing-machine embodying the invention, the near side being removed and parts shown in section. Fig. 2 is a section on the line X X of 35 Fig. 3, looking to the left, as indicated by the arrow. Fig. 3 is a sectional detail view on a larger scale, showing the ordinary fan, the auxiliary fan, the shoe, the rear portion of 40 the conveyer, and the parts immediately connected therewith.

The thrashing-machine in its general construction comprises the usual parts, consisting of the cylinder 1, concave 2, beater 3, grates 4 and 5 beneath the cylinder and beater, straw-rack 6, conveyer 7, shoe 8, grain-auger 9, tailings-auger 10, stacker 11, fan 12, elevator 13, and tailings-spout 14.

The auxiliary or supplemental fan 15 is considerably 50 smaller than the ordinary fan 12, and is located nearer the front end of the machine, and has a spout 16, which curves up-

wardly and rearwardly over the fan 12. The fans 15 and 12 are of ordinary construction and disposed in approximately the same horizontal plane. 55

A long lip-sieve 17 is located at the rear end portion of the conveyer 7 immediately over the shoe 8, and an inclined lip-sieve 18 is arranged at the front end of the sieve 17 60 and over the discharge-spout of the fan 12. The inner ends of the sieves 17 and 18 are sustained by a support 19. The lip-sieves 17 and 18 are formed from sheet metal, which have the openings formed therein by punching lips in the ordinary manner common in the construction of sieves for this class of machinery. An incline 20 is provided at the forward end of the shoe 8 and immediately below the sieve 18, and is designed to guide the grain 65 falling thereon from the sieve 18 into the shoe. A piece of sheet metal 21 is located at the upper end of the incline 20 and between it and the end of the spout 16, and is designed to prevent the grain passing over the front edge 70 of the incline 20. A block 22 is interposed between the side rail and the support for the rear end of the conveyer to elevate the latter a sufficient distance to admit of the spout 16 75 coming between its lower side and the top of 80 the fan 12.

There will be one block, 22, for each side of the machine, and in addition to raising the rear end portion of the conveyer 7 it also serves to raise the rear end of the straw-rack 85 6, thereby preventing the grain from passing over the rear end of the latter with the straw.

On reference to Fig. 2 it will be seen that the shaft 23 has crank portions 24 near its ends, to which the rods 25 are attached, by 90 means of which motion is imparted to the straw-rack and conveyer in the usual manner. The auxiliary fan 15 is of such length as to come between the crank portions 24, but the spout 16 will be spread at its delivery 95 end so as to occupy the full width of the machine and deliver the blast of air upon the full width of the sieves 18 and 17.

In its general operation the machine does not differ materially from others of similar 100 construction until the grain is delivered from the conveyer onto the sieves 17 and 18, when it is met by the blast of air from the auxiliary fan 15, which carries off the bulk of the chaff

and other light foreign matter. The grain upon the sieves 17 and 18, and in falling from the same onto the shoe and incline 20, is subjected to the blast from the auxiliary fan 15, 5 and is not acted upon by the blast from the ordinary fan 12 until it reaches the shoe 8.

From the foregoing it will be seen that the two fans 12 and 15 act independently, but unitedly effect a unitary result and thoroughly and effectually clean the grain from 10 all light and foreign matter. The blasts from each of the fans can be so regulated as not to blow the grain from the sieves, which would be the result if the two fans combined their 15 blasts and acted on the grain at one operation. It will be seen that the blast from the fan 15 treats the grain before the latter reaches the shoe, and that the grain in its passage through the shoe is subjected to the blast from the ordinary fan 12, which removes the last traces 20 of chaff and light foreign substances.

It will be seen that the separating-sieves 17 and 18 incline in opposite directions, the sieve 18 being considerably shorter and disposed at 25 a greater inclination than the sieve 17, and coming opposite the spout 16 receives the full blast of air from the fan 15 and deflects the said blast through the passage formed between the sieve 18 and the inclines 20 and 21 30 and beneath the sieve 17, thereby carrying off the bulk of the chaff and like particles. The forwardly and downwardly extending lips of the sieves 17 and 18 catch and direct a portion of the blast upwardly through the sieves 17 and 18, thereby lightening and loosening the grain so as to enable it the better to 35 pass through the sieves besides carrying off a quantity of the dust and light matter. The inclines 20 and 21 catch what grain drops 40 through the openings of the sieve 18 and direct it to the shoe, and these inclines are located above the spout of the ordinary fan 12 and

prevent the grain lodging thereon. The provision of the blocks 22 admits of the invention being applied to separators now in use, in 45 that simple and effective means are had for elevating the conveyer a sufficient distance to admit of the curved spout 16 extending over the fan 12, so as to deliver the blast of air against the upwardly and forwardly inclined 50 sieve 18 to effect the initial cleaning of the grain.

By the present invention the auxiliary fan 15 can be applied to any of the usual makes of grain-separators without requiring a reconstruction of the same and at a slight cost 55 above the expenditure required for the operating parts.

The shoe 8 is vibrated from an eccentric on the shaft of the fan 12 in the usual manner, 60 and has connection with the said eccentric by means of a rod 26 and a bracket-casting 27, the latter being provided on the shoe.

Having thus described the invention, what is claimed as new is—

In a thrashing-machine, the combination with the shoe, a fan arranged at the front end of the shoe, and a conveyer provided with oppositely-inclined lipped sieves, of blocks interposed between the side rails of the frame 70 and the conveyer to elevate the latter a proper distance, and an auxiliary fan arranged in the front of the ordinary fan and having a spout curving rearwardly and upwardly and extending between the lower side of the conveyer and the top portion of the ordinary fan, 75 substantially as and for the purpose set forth.

In testimony that I claim the foregoing as my own I have hereto affixed my signature in the presence of two witnesses.

HARVEY S. BONNELL.
